US0D1022086S

(12) **United States Design Patent** (10) **Patent No.:** **US D1,022,086 S**
(45) **Date of Patent:** **** Apr. 9, 2024**

(54) **LAP PAD ASSEMBLY FOR EXERCISE APPARATUS**

(71) Applicant: **Expectations, LLC**, Bonney Lake, WA (US)

(72) Inventors: **Nicholas M. Soller**, Orting, WA (US); **Christopher H. Leier**, Lake Tapps, WA (US); **Darrin M. Swagel**, St. Louis Park, MN (US)

(73) Assignee: **Expectations, LLC**, Bonney Lake, WA (US)

(**) Term: **15 Years**

(21) Appl. No.: **29/841,921**

(22) Filed: **Jun. 9, 2022**

(51) **LOC (14) Cl. 21-02**

(52) **U.S. Cl.**

(57) **CLAIM**

The ornamental design for a lap pad assembly for exercise apparatus, as shown and described herein.

DESCRIPTION

FIG. 1 is a front perspective view of a lap pad assembly for exercise apparatus showing our new design;

FIG. 2 is a front view thereof;

FIG. 3 is a rear view thereof;

FIG. 4 is a bottom view thereof;

FIG. 5 is a top view thereof;

FIG. 6 is a first side view thereof;

FIG. 7 is a second side view thereof; and,

FIG. 8 is a front perspective view, showing the lap pad assembly for exercise apparatus in use.

The portions of the lap pad assembly for exercise apparatus shown in broken lines form no part of the claimed design. Broken lines in FIG. 8 showing environment form no part of the claimed design.

1 Claim, 8 Drawing Sheets
